CIRCUIT BREAKER CONTROL SYSTEM

Maurice E. Reagan and Guy W. Champney,
Pittsburgh, Pa., assignors to Westinghouse
Electric & Manufacturing Company, East
Pittsburgh, Pa., a corporation of Pennsylvania

Application December 16, 1941, Serial No. 423,190

7 Claims. (Cl. 175—294)

Our invention relates, generally, to circuit breaker control systems, and, more particularly, to control systems embodying antipumping means and means for positively closing and latching circuit breakers.

In previously known circuit breaker closing systems in which a plurality of relays have been employed to close a circuit breaker and have been interconnected to prevent pumping of the breaker, it has been found that the relay system often releases before the circuit breaker latches in closed position, thus resulting in failure of the circuit breaker to positively close and latch.

It is an object of our invention to provide a circuit breaker control system which shall function to so control a circuit breaker as to positively close and latch the breaker, and which shall be simple and efficient in operation and inexpensive to manufacture, install, operate, and maintain.

These and other objects and advantages of the invention will be apparent from the following detailed description taken in connection with the accompanying drawing, in which like reference characters indicate like parts in the several figures, and in which,

Figures 1, 2, and 3 are each a diagrammatic view of a circuit breaker control system embodying the principal features of the invention.

In practicing the invention, in the embodiment of Fig. 1, a circuit breaker 4 having a trip-free operating mechanism including a closing coil 6 and a trip coil 8 is shown. A relay 10 controls the closing coil 6 and is, in turn, controlled by a relay 12 and a "close" circuit control device 14. The relay 12 is held energized in a circuit which includes a reactor 18 which is rendered operative to slowly decrease the energization of the relay 12 when the circuit breaker closes to thereby continue the energization of the relay 10 and the closing coil 6 for an interval after the breaker has closed, thereby insuring that the breaker will be positively closed and latched before release of the closing coil 6.

The embodiment of the invention shown in Fig. 2 is a circuit breaker control system such as may be employed at automatic stations and includes a master relay 20 through which the relays 10 and 12, the reactor 18, and the closing and trip coils 6 and 8 function in a manner similar to the system of Fig. 1.

The system of Fig. 3 is an automatic reclosing system embodying the principles of the closing elements of the systems of Figs. 1 and 2, and including an automatic timing means 22 in the 55

form of a recloser for preventing the breaker 4 from closing in the event that it trips within a predetermined time after any closure.

Considering the invention more in detail with reference to Fig. 1, the circuit breaker 4 may be disposed to connect a power bus, represented by the conductors 24 and 26, with a distribution line including conductors 28 and 30. A source of alternating current control power, represented by the conductors 32 and 34, may be provided.

The closing coil 6 of the circuit breaker 4 operates against the bias of a spring member 36 and through engaging detents 38 and 40 to move the linkage 42 against the bias of a spring member 55 to close the circuit breaker. When the circuit breaker is in closed position, a detent 46 on an arm 50 which actuates the linkage 42 will be engaged by a spring-pressed detent 48 to hold the circuit breaker in closed circuit position. The trip coil 8 of the circuit breaker when energized will function to move the arm 50 downwardly to disengage the detent 46 from the detent 48 and permit the spring member 44 to actuate the linkage 42 to move the circuit breaker to open circuit position.

An energizing circuit is provided for the relay 10 extending from the conductor 34 through conductors 52 and 54, the winding of the relay 10, a conductor 56, a contact element 58 of the relay 12, a conductor 60, the contact element of the "close" circuit control device 14, and the conductors 62 and 64 to conductor 32. The relay 10 controls an energizing circuit for the closing coil 6 of the circuit breaker 4 extending from the conductor 32 through conductors 66 and 68, a contact element 70 of the relay 10, a conductor 72, a rectifier 74, conductors 76 and 78 extending between the rectifier 74 and the closing coil 6, and conductor 80 to the conductor 34.

An energizing circuit for the relay 12 extends from the conductor 32 through conductors 66 and 32, the contact element of the circuit control device 14, a conductor 84, the contact element of a "trip" circuit control device 86, conductors 88 and 90, the winding of the relay 12, and the conductor 52 to the conductor 34. The relay 12 controls its own holding circuit through its contact element 92 which circuit extends from the conductor 32 through the conductor 66, the contact element 92, conductors 94 and 96, a winding 98 of the reactor 18, a conductor 100, another winding 102 of the reactor 18, the conductor 90, the winding of the relay 12 and the conductor 52 to the conductor 34.

Another winding 104 of the reactor 18 is ener-

gized with direct current power in a circuit which extends from the conductor 32 through the conductor 66, the contact element 92, the conductor 94, a rectifier 106, a conductor 108, the winding 104, conductors 110 and 111, a resistor 112, and a conductor 114 to the conductor 34. A shunting circuit is provided for the reactor winding 104 which extends from one terminal of the winding 104, through conductors 108 and 116, the contact element 16, and conductor 110 to the other terminal of the winding 104.

The windings 98, 102 and 104 of the reactor 18 are disposed as indicated on a common core 118. The direct current energization of the winding 104 is such that this winding saturates the core 118 and thereby minimizes the impedance of the windings 98 and 102 which are connected in the holding circuit of the relay 12 to thereby insure full energization of the winding of the relay 12. When the closing coil 6 of the circuit breaker moves the contact element 16 to closed circuit position, the shunting circuit for the winding 104 will be closed and will cause the direct magnetizing current flowing in the coil 104 to be reduced to practically zero. The collapse of the direct current flux in the core 118 will require an interval of time, and when it is completed the reactance of the windings 98 and 102 will be so increased as to prevent sufficient current to flow in the winding of the relay 12 to maintain it actuated through its holding circuit.

An energizing circuit for the trip coil 8 of the circuit breaker 4 extends from the conductor 32 through the conductors 64 and 62, the contact element of the circuit control device 86, in actuated position, conductors 120 and 122, the winding of the trip coil 8, a conductor 124, a contact element 125 actuated by the circuit breaker 4, and a conductor 126 to the conductor 34. Another energizing circuit for the trip coil 8 is controlled by a potential responsive relay 127, and extends from the conductor 32 through a conductor 128, a contact element 130 of the relay 127, the conductor 122, the winding of the trip coil 8, the conductor 124, the contact element 125, and the conductor 126 to the conductor 34.

In the operation of the embodiment of the invention of Fig. 1, when it is desired to close the circuit breaker 4, the "close" circuit control device 14 may be manually actuated to close the energizing circuit for the relay 10. The actuation of the relay 10 will close the energizing circuit for the closing coil 6 which will close the circuit breaker 4 and move the contact element 16 to circuit closing position. The closing of the shunting circuit for the reactor winding 104 will gradually increase the impedance of the holding circuit of the relay 12 and cause the relay 12 to release after an interval of time. When the relay 12 has released the relay 10 will be released and will, in turn, deenergize the closing coil 6. Thus the energization of the closing coil 6 will be maintained for an interval of time after it has closed the circuit breaker to thereby insure that the circuit breaker will be fully and positively closed, and that the detent 43 has ample time to engage the detent 46 to hold the circuit breaker in closed position.

The circuit breaker 4 is prevented from "pumping" when the circuit control device 14 is held actuated by the fact that the original energizing circuit for the relay 12 extends through the contact element of the circuit control device 14 in released position. Therefore, it is necessary that

control device 14 be released before there is another closure of the circuit breaker 4.

In the embodiment of the invention of Fig. 2, the energizing circuit for the relay 10 extends from the conductor 34 through the conductors 132, 134, and 135, the winding of the relay 10, a conductor 136, a contact element 138 of the relay 12, a conductor 140, a contact element 142 of the relay 20, and conductors 144 and 146 to the conductor 32.

The contact element 70 of the relay 10 controls an energizing circuit for the closing coil 6 extending from the conductor 34 through the conductors 132 and 134, the contact element 70, the conductor 72, the rectifier 74, the conductors 76 and 78 which extend between the rectifier 74 and the winding of the closing coil 6, and a conductor 80 to the conductor 32.

The energizing circuit for the relay 12 extends from the conductor 32 through the conductors 146 and 148, a contact element 150 of the relay 20, conductors 152 and 154, the winding of the relay 12, and the conductor 132 to the conductor 34. A holding circuit for the relay 12 extends from the conductor 32 through the conductor 146, a contact element 156 of the relay 12, conductors 158 and 160, reactor winding 98, the conductor 162, reactor winding 102, the conductor 154, the winding of the relay 12, and the conductor 132, to the conductor 34. The reactor 18 is a substantial duplicate of that described in connection with the system of Fig. 1, and has like reference characters applied to corresponding elements. The shunting circuit for the direct current winding 104 of the reactor 18 is controlled by contact element 16, and described hereinbefore in connection with the system of Fig. 1.

An energizing circuit is provided for the relay 20 and extends from the conductor 34 through a conductor 162, a "close" circuit control device 164, a conductor 166, a contact element 168 of a voltage responsive relay 169, conductors 180, 182 and 184, the winding of the relay 20, a conductor 186, a resistor 188, a conductor 190, a contact element 192 and a conductor 194 to the conductor 32. A holding circuit for the relay 20 extends from the conductor 34 through conductors 132 and 196, a contact element 198 of the relay 20, the conductor 164, the winding of the relay 20, the conductor 185, the resistor 188, the conductor 190, the contact element 192, and the conductor 194 to the conductor 32.

The relay 20 may be released by a shunting circuit controlled by a back contact element 200 of the voltage responsive relay 169 which extends from one terminal of the winding of the relay 20 through conductors 184, 182 and 180, the contact element 200, and conductors 202 and 186 to the other terminal of the winding of the relay 20. A shunting circuit for releasing the relay 20 is also controlled by a "trip" contact element 204 and extends from one terminal of the winding of the relay 20 through the conductors 184 and 182, the contact element 204, and conductors 202 and 186 to the other terminal of the winding of the relay 20.

The "close" contact element 164 and the "trip" contact element 204 may be contact elements controlled by a remote control system from a control station over which the apparatus including the circuit breaker 4 disposed at a remote station is controlled and/or supervised.

A relay 206 is connected to be controlled by a contact element 208 in a circuit extending from

the conductor 34 through a conductor 210, the contact element 208, a conductor 212, the winding of the relay 206, conductors 214 and 190, the contact element 192 and the conductor 194 to the conductor 32. The relay 206 is disposed to actuate a detent 216 against the bias of a spring member 218 from engagement with a detent 220 to permit the contact element 192 to drop to open circuit position to thereby break the energizing and holding circuits for the relay 20. The contact element 208 may be actuated by any device at the station at which the circuit breaker 4 is installed, responsive to a condition such that it is undesirable that the circuit breaker 4 be again closed until after inspection of the equipment controlled by the circuit breaker 4. The contact element 192 will remain in open circuit position until manual actuation of the member 221 moves it to closed circuit position where the detent 216 will cooperate with the detent 220 to hold the contact element 192 in closed circuit position.

In the operation of the system of Fig. 2, when it is desired to close the circuit breaker the contact element 164 may be actuated to close an energizing circuit for the relay 20 which will pick up and close its own holding circuit as hereinbefore described. Actuation of the relay 20 will cause the relay 10 to be energized, and the relay 10 will, in turn, energize the closing coil 6 of the circuit breaker 4. The relay 12 will be energized through its own holding circuit and the reactor 18 until the contact element 16 is moved to circuit closing position by the closing coil 6 at which time the reactor winding 104 will be shunted and the impedance of the reactor windings 98 and 102 will so increase after a time interval as to cause the relay 12 to be released. The release of the relay 12 will open the energizing circuit for the relay 10 which, in turn, will deenergize the closing coil 6, after a sufficient time interval to permit the breaker to be fully and positively closed and to permit the detent 48 to positively engage the detent 46 to hold the circuit breaker 4 in closed circuit position.

In the embodiment of the invention of Fig. 3, the relay 10 has an energizing circuit which extends from the conductor 34, conductors 132, 134, and 135, the winding of the relay 10, a conductor 222, a contact element 224, which is mounted upon an arm 225 and biased to the position to which it is actuated by circuit control devices 226 and 227 by a spring member 228, a conductor 230, a contact element 232 of the relay 12 and conductors 234 and 236 to the conductor 232. The relay 10 controls an energizing circuit for the closing coil 6 which extends from the conductor 34 through the conductors 132 and 134, the contact element 70 of the relay 10, the conductor 72, the rectifier 74, the conductors 76 and 78 which extend between the rectifier 74 and the closing coil 6, and the conductor 82 to the conductor 32.

An energizing circuit for the relay 12 extends from the conductor 32 through conductors 238, 240 and 241, a contact element 242, a conductor 244, a contact element 246 which is actuated by the circuit breaker 4 in open circuit position, a conductor 248, a conductor 250, the winding of the relay 12 and the conductor 132 to the conductor 34. The circuit control device 226, when actuated, also closes an energizing circuit for the relay 12 which extends from the conductor 32, through conductors 252 and 254, a contact element of the circuit control device 226, conductors

248 and 250, the winding of the relay 12 and the conductor 132 to the conductor 34. A holding circuit for the relay 12 extends from the conductor 32, through the conductor 236, a contact element 256 of the relay 12, a conductor 258, the reactor winding 98, the conductor 100, the reactor winding 102, the conductor 250, the winding of the relay 12 and the conductor 132 to the conductor 34.

The direct current winding 104 of the reactor 18 is energized in a circuit which extends from the conductor 34 through conductors 260, 262, and 264, the rectifier 106, a conductor 266, the direct current reactor winding 104, a conductor 268, a resistor 270 and conductors 272 and 236 to the conductor 232. A shunting circuit for the direct current reactor winding 104 is controlled by the contact element 16 and extends from one terminal of the winding 102 through the conductors 266 and 274, the contact element 16 and conductors 276 and 268 to the other terminal of the winding 104.

An energizing circuit for the trip coil 8 extends from the conductor 32 through the conductors 252 and 254, the contact element of the circuit control device 227, conductors 278 and 280, the winding of the trip coil 8, a conductor 282, a contact element 284 actuated by the circuit breaker 4 in closed circuit position, and conductors 262 and 260 to the conductor 34. An overload or any other suitable type of protective relay 286 also controls an energizing circuit for the trip coil 8 which extends from the conductor 32 through the conductor 288, a contact element 290 of the relay 286, the conductors 278 and 80, the winding of the trip coil 8, the conductor 282, the contact element 284 and conductors 262 and 260 to the conductor 34.

The timing device or recloser 22 comprises a timing element 292 which is connected in a circuit controlled by a contact element 294 and the contact element 246 in front contact position extending from the conductor 32 through the conductor 238, the contact element 294, a conductor 296, the timing element 292, a conductor 298, the contact element 246 and the conductor 260 to the conductor 34. The timing element 292 moves a contact member 300 to circuit closing position after a predetermined interval of energization.

The contact elements 242 and 294 are disposed to be moved into the right-hand position in which they are shown in the drawing by a coil 302 and to a left-hand position by a coil 304, and are adapted to remain in the positions to which they are moved by the coils 302 and 304. The coil 304 is controlled by the contact element 70 of the relay 10 in a circuit which extends from the conductor 34, through the conductors 132 and 134, the contact element 70, conductors 72 and 306, the coil 304, and conductors 240 and 238 to the conductor 32. The coil 302 is connected to be energized in a circuit which extends from the conductor 32 through the conductors 238 and 240, the contact element 242 in the left-hand position, a conductor 308, the coil 302, a conductor 310, the contact element 300, a conductor 312, a contact element 314 actuated by the circuit breaker 4, and conductors 262 and 260 to the conductor 34.

In the operation of the embodiment of the invention of Fig. 3, the circuit control device 226 may be actuated. If the relay 12 is not energized in the circuit controlled by the contact element 242, the circuit control device 226 will close an energizing circuit for the relay 12 and the con-

tact element 232 of the relay 12 and the contact element 224 actuated by the circuit control device 226 will close an energizing circuit for the relay 10. The actuation of the relay 10 will close the energizing circuit for the closing coil 6 which will cause a circuit breaker 4 to be closed. The contact element 18 actuated by the closing coil 6 will close the shunting circuit for the direct current reactor winding 104 which will gradually increase the impedance of the holding circuit for the relay 12 and cause the relay 12 to be released after a short interval of time. The relay 10 and the closing coil 6 will be released upon the release of the relay 12 a sufficient interval after the closure of the relay 4 to insure positive closure of the circuit breaker and positive latching of the circuit breaker in closed position by the detents 46 and 48.

The actuation of the relay 10 causes the coil 304 to be energized to move the contacts 242 and 294 to the lefthand circuit closing position. The contact elements 294 and 246 will cause the timing element 292 to be energized, and, after a time interval determined by the adjustment of the timing element 292, the contact member 300 will be actuated to circuit closing position to energize the coil 302 which will move the contact elements 242 and 294 to the righthand position shown in the drawing.

Should an overload or any other fault on the load conductors 28 and 30 cause the relay 286 to trip the circuit breaker 4, the energizing circuit for the relay 12 will be completed by the contact element 246 in back contact position to immediately actuate the relay 12, whose contact element 232 will close the energizing circuit for the relay 10. The actuation of the relay 10 will close the energizing circuits for the closing coil 6 and the coil 304, and the circuit breaker will be reclosed immediately. With the contact element 242 in the left-hand position to which it has been moved by the coil 304, the energizing circuit for the relay 12 cannot again be energized until the timing element 292 has caused the coil 302 to return the contact element 242 to the right-hand circuit closing position. Thus, should the circuit breaker again trip immediately after any closure, it will be held open by the failure of the relay 12 to pick up and cause the relay 10 to energize the closing coil 6.

When the circuit breaker 4 is opened by the actuation of the circuit control device 227, the contact element 224 will be moved to open circuit position and held in that position by the spring member 228, thus preventing reclosure of the circuit breaker 4 until the circuit control device 223 is also actuated.

It is to be understood that the relays 127 and 169 of Figs. 1 and 2 respectively are merely illustrative of one type of protective relay and that protective relays such as the fault relay 286 of Fig. 3 may be employed instead of or in addition to the relays 127 and 169 to perform the functions of controlling the circuits controlled by the relays 127 and 169.

Thus it will be seen that we have provided a circuit breaker control system which shall function to so control a circuit breaker as to positively close and latch the breaker, and which shall be simple and efficient in operation and inexpensive to manufacture, install, operate and maintain.

In compliance with the requirements of the patent statutes, we have shown and described herein the preferred embodiments of our inven-

tion. It is to be understood, however, that the invention is not limited to the precise constructions shown and described, but is capable of modification by one skilled in the art, the embodiments herein shown being merely illustrative of the principles of our invention.

We claim as our invention:

1. In a circuit breaker control system, a first relay for energizing the closing means of the circuit breaker, a second relay for energizing the first relay, and means responsive to the closing of the breaker for releasing the second relay comprising a reactor connected in circuit with the winding of the second relay, a saturating means for the reactor and means responsive to the closure of the breaker for rendering the saturating means inoperative.

2. In a circuit breaker control system, a first relay, an energizing circuit for the closing means of the circuit breaker including a front contact element of the first relay, a second relay, an energizing circuit for the first relay including a front contact element of the second relay, a reactor having a first and a second winding, means for so energizing the first reactor winding as to saturate the reactor core, an energizing circuit for the second relay including the second reactor winding, and means responsive to the closure of the breaker for deenergizing the first reactor winding.

3. In a circuit breaker control system, a first relay, an energizing circuit for the closing means of the circuit breaker including a contact element of the first relay, a second relay, an energizing circuit for the first relay including a contact element of the second relay, a reactor having a first and a second winding, means for so energizing the first reactor winding with direct current as to saturate the reactor core, an alternating current energizing circuit for the second relay including the second reactor winding, and circuit means responsive to the operation of the closing mechanism of the breaker for shunting and thereby decreasing the energization of, the first reactor winding.

4. In a circuit breaker control system, a first relay connected to energize the closing means of the circuit breaker, a circuit control device, a second relay, an energizing circuit for the first relay including a front contact element of the circuit control device and a contact element of the second relay, a reactor having a first and a second winding, means for so energizing the first reactor winding with direct current as to saturate the reactor core, a first alternating current energizing winding for the second relay including the second reactor winding, a contact element of the second relay and second reactor winding, a second energizing winding for the second relay including a back contact element of the circuit control device, and means responsive to the actuation of the circuit breaker closing means for decreasing the energization of the first reactor winding sufficiently to cause the release of the second relay.

5. In a circuit breaker control system, a first relay for energizing the circuit breaker closing means, a second relay, and a third relay, an energizing circuit for the first relay including contact elements of the second and third relays, an energizing circuit and a holding circuit for the third relay, a first energizing circuit for the second relay including a back contact element of the third relay, a reactor having a first and a second winding, means for so energizing the

first reactor winding as to saturate the reactor core, a second alternating current energizing circuit for the second relay including the second reactor winding and a contact element of the second relay, and means responsive to the actuation of the circuit breaker closing means for decreasing the energization of the first reactor winding sufficiently to release the second relay.

6. In a circuit breaker control system, a first relay, a second relay, a third relay, circuit means whereby actuation of the first relay causes the circuit breaker closing means to operate, an energizing circuit for the first relay including a contact element of the second relay, an energizing circuit for the third relay including a control element of the first relay, a first energizing circuit for the second relay including a back contact element operated by the circuit breaker and a contact element actuatable to open circuit position by the third relay, a reactor having a first and a second winding, means for so energizing the first reactor winding with direct current as to saturate the reactor core, a second energizing circuit for the second relay including a contact element of the second relay and the second reactor winding, and means responsive to the actuation of the circuit breaker closing means for decreasing the energization of the first reactor winding sufficiently to release the second relay.

7. In a circuit breaker control system, a first relay, a second relay, a third relay, circuit means whereby actuation of the first relay causes the circuit breaker closing means to operate, an energizing circuit for the first relay including a contact element of the second relay, an energizing circuit for the third relay including a contact element of the first relay, a first energizing circuit for the second relay including a back contact element operated by the circuit breaker and a contact element actuatable to open circuit position by the third relay, a reactor having a first and a second winding, means for so energizing the first reactor winding with direct current as to saturate the reactor core, a second energizing circuit for the second relay including a contact element of the second relay and the second reactor winding, means responsive to the actuation of the circuit breaker closing means for decreasing the energization of the first reactor winding sufficiently to release the second relay, and time delay means responsive to the actuation of the third relay and the closure of the circuit breaker for reclosing the contact element actuated by the third relay a predetermined time after the closure of the circuit breaker.
